SOLE CONSTRUCTION FOR APPAREL SHOES

Application filed May 7, 1928, Serial No. 275,584. Renewed May 5, 1931.

This invention relates generally to apparel shoes, and more specifically to an improved sole construction therefor, the predominant object of the invention being to secure the 5 fibre-board, which ordinarily forms a part of the sole construction of a shoe of a certain type, to the insole of the shoe in a manner to provide a pocket in which the arch shank of the shoe is arranged, whereby the manufacture 10 of the shoe is simplified and said shoe is made more durable.

Many shoes, and particularly ladies' shoes of the French or high heel type, are provided with an element which forms a part of the 15 sole construction thereof, which is known as the fibre-board. This element, which is intended to give additional stiffness to the arch portion of the shoe, is made from material which is relatively tough and stiff when compared with the material from which the in- 20 sole of the shoe is formed, and ordinarily said element extends from the approximate rear edge of the heel portion of the shoe to the portion of the sole known as the break, 25 or in other words, the curved line at which the ground contacting portion of the outsole joins the upwardly curved shank portion of said outsole. Heretofore, the fibre-boards referred to were unattached to the insoles of 30 the shoes prior to the time said insoles were tacked to the lasts on which the shoes were to be constructed, and the arch shanks heretofore were merely loosely interposed between the insoles and the fibre-boards before 35 these parts were attached together by being tacked to the lasts. As a result of this arrangement, the task of attaching an insole with its associated elements to a last was rendered quite difficult and was caused to con- 40 sume more time than desirable due to the fact that the operator had to handle and manipulate three separate pieces of material.

In accordance with the present invention, the fibre-board is stitched or otherwise se- 45 cured directly to the insole before said insole is attached to the last, said fibre-board being secured to said insole in such manner that a pocket is formed between the insole and the fibre-board, in which pocket the arch shank 50 of the shoe is located, whereby said arch shank

is maintained in a flexed position with respect to the insole and the fibre-board. By virtue of this arrangement, a unitary sole construction is produced which is comprised of the insole, the fibre-board, and the arch shank, 55 and because of this unitary construction the task of attaching the insole with its associated elements to the last is much simplified, and also the sole construction of the shoe is made more durable. 60

Figure 1 is an inverted plan view of our improved unitary sole construction showing an insole, a fibre-board, and an arch shank in permanent association with each other;

Figure 2 is a view partly in side elevation 65 and partly in vertical section showing a shoe constructed in accordance with the present invention;

Figure 3 illustrates a modified form of the invention. 70

In the drawings, which illustrate one embodiment merely of the invention, A designates a lady's shoe (Fig. 2) constructed in accordance with the present invention, said shoe comprising an outsole B and upper portions C. 1 designates the insole of the shoe A which insole, as shown clearly in Fig. 2, is split longitudinally, said split portion being extended forwardly from the edge of the rear or heel portion of the insole to a point forward of the front edge of the heel E of the shoe. The split heel portion of the insole 1 provides said insole at this point with a lower flap portion 2 and an upper flap portion 3, which flap portions are integrally connected together at their inner ends. While we prefer to provide the insole of our improved shoe construction with the flap portions 2 and 3 by splitting the insole longitudinally, it is obvious that one or the other of said flap portions may be separate and may be secured to the associated flap portion in any suitable manner. 85

The reference numeral 4 designates the fibre-board of our improved shoe construction, said fibre-board being of a shape which corresponds approximately with the shape of the rear portion of the insole 1. The fibre-board 4 is arranged in contact with the lower face of the insole of the shoe, as shown in Fig. 90 100

2, said fibre-board being of such dimensions that its side edges and its rear edge are spaced inwardly a slight distance from the corresponding side and rear edges of the associated insole, and said fibre-board extends 5 from the approximate rear edge of the insole to a point slightly forward of the break of the shoe, or in other words, the point at which the ground contacting portion of the outsole 10 joins the upwardly curved shank portion of said outsole. The fibre-board 4 is secured to the insole 1 in any suitable manner to provide a pocket between said fibre-board and said insole, but we prefer to effect the attachment 15 of said elements by forming a row of stitches 5 which pass through said fibre-board and said insole and which are arranged parallel with the forward portions of side marginal edges and of the front edge of said 20 fibre-board, as shown in Fig. 1. The stitches 5 terminate some distance short of the rear portions of the fibre-board and the insole, so that said rear portion of the fibre-board is unattached to the insole, and hence may be separated 25 therefrom to permit access to the pocket formed between said fibre-board and said insole.

The reference numeral 6 designates the arch shank of our improved shoe construction, said arch shank being formed of any suitable material and having a relatively narrow forward portion 6a and a rear or heel portion 6b which is of approximately the same shape as the rear or heel portion of the 30 insole 1 and fibre-board 4 (Fig. 1). The arch shank 6 is introduced into the pocket formed between the insole and the fibre-board by lifting the rear portion of said fibre-board and moving the portion 6a of said arch shank 35 longitudinally of said pocket until movement of the arch shank is arrested by the closed forward end of the pocket. When the arch shank has been arranged in the pocket as described, the enlarged heel portion thereof 40 will be positioned properly with respect to the heel portions of the insole 1 and fibre-board 4, as shown in Fig. 1. It is obvious, in view of this arrangement of the insole, fibre-board, and arch shank, that a unitary 45 sole construction is produced which permits of said elements being handled as a unit, and because of this unitary construction, the task of temporarily securing the insole, fibre-board, and arch shank to the last is greatly 50 simplified, this simplification of said task resulting from the fact that it is not necessary for the operator to handle and manipulate three separate elements, as was the case prior 55 to this invention.

60 In the manufacture of a shoe in accordance with our invention, the insole, with its associated elements, and the upper portions C, are secured to the last in the usual manner. The outsole is then arranged in place on the 65 last, and the outsole, insole, and upper por-

tion at the toe of the shoe are stitched or otherwise secured together in the ordinary manner. The outsole, insole, and heel portion of the upper are also secured together in the usual manner by tacks which are driven from the outside of the shoe through the outsole and insole and in-turned portion of the heel portion of the upper, but the tacks used for securing these portions together are of such length that they will pass only through the lower 75 flap 2 of the insole and will not extend into the upper flap portion 3 thereof.

When the outsole, insole and upper portions of the shoe have been secured together as described, the heel E will be arranged in place on the shoe, and when the upper flap portion 3 of the insole has been moved upwardly to the position in which it is shown by dotted lines in Fig. 2, nails or other fastening devices 7 will be driven from the inside 80 of the shoe through the lower flap 2 of the insole 1 through apertures 8 in the heel portion of the arch shank 6 and through the fibre-board 4 and the outsole B into the heel E, whereby said heel will be secured in place. 85 The apertures 8 may be located by passing a sharp-pointed instrument, such as an awl, from beneath through said apertures and through the lower flap 2. After the fastening devices 7 have been driven into the heel 90 as described, the upper flap portion 3 of the insole 1 will be moved downwardly to its normal position in contact with the upper face of the lower flap 2, and said upper flap portion will then be cemented or otherwise 95 secured in this position. It is obvious when the upper flap portion 3 has been secured in its normal position as described, that said upper flap portion will effectively cover the heads of the fastening devices 7 and will also 100 function as a cushion between the heel portion of the arch shank and the heel of the wearer of the shoe.

Due to the fact that the arch shank of our improved shoe structure extends to the rear 110 end of the shoe instead of terminating adjacent to the front edge of the heel, as was usually the case heretofore, and also because the heel portion of the shank is shaped to conform to the shape of the heel portion of the shoe and is rigidly secured in place by the nails which secure the heel to the shoe, our improved shoe is greatly strengthened at the point where shoes of this type were formerly rather weak, and, therefore, the 115 tendency for the outsole of the shoe to be broken at the front edge of the heel is eliminated. Also, it is pointed out that while the shoe is given additional strength where 120 needed by our improved construction, still the desired flexibility of the shoe at the arch portion thereof is not interfered with. The 125 fact that the arch shank of our improved shoe construction is located within a pocket formed on the insole results in said arch 130

shank being maintained in its proper position with respect to the other elements of the sole construction at all times, and this adds greatly to the durability of the shoe.

5 In Fig. 3, we show a modified form of our invention in accordance with which the insole 1' has fixed to it a fibre-board 4'. The fibre-board 4' is secured to the insole 1' by means of rows of stitches 5' which pass through said fibre-board and said insole and are arranged parallel with the opposite side edges of the fibre-board at the forward portion thereof. In the construction shown in Fig. 3, the fibre-board 4' is not stitched to the insole along the forward edge of said fibre-board, as is the case in the preferred construction of the invention, as illustrated in Fig. 1. The stitches 5' shown in Fig. 3 terminate short of the rear or heel portion of the fibre-board 4', so that the arch shank 6' may be introduced into the pocket formed between the insole and the fibre-board by lifting the rear portion of the fibre-board and moving the forward portion of the arch shank longitudinally of said pocket.

20 While we describe the fibre-board 4 as being secured to the insole 1 of the shoe to provide same with a pocket to receive the arch shank, it is obvious that said fibre-board may be secured to the inner face of the outsole B, and also we, if desired, may secure the fibre-board 4 to the inner face of the insole 1 instead of the outer face thereof, as described.

25 We claim:

30 1. An apparel shoe comprising an outsole, an insole, a fibre-board secured to said insole to provide a pocket, an arch shank located within said pocket, and a heel, said insole having separable portions arranged one above 35 the other at the heel portion thereof, and fastening devices extended through the lowermost of said separable portions of said insole through said arch shank and fibre-board and through said outsole into said heel.

40 2. An apparel shoe comprising an outsole, an insole, a fibre-board secured to said insole to provide a pocket, an arch shank located within said pocket, a heel, said insole having separable portions arranged one 45 above the other at the heel portion thereof, and fastening devices extended through the lowermost of said separable portions of said insole through said arch shank and fibre-board and through said outsole into said heel, 50 the uppermost of said separable portions of said insole being adapted to cover the head 55 portions of said fastening devices.

3. An apparel shoe comprising an outsole, an insole, a fibre-board secured to said insole 60 to provide a pocket, and an arch shank located within said pocket, said fibre-board being stitched to said insole along its forward edge and along the forward portions of its opposite side edges and being unattached to 65 said insole at its rear portion, whereby access

may be had to the interior of the pocket formed thereby.

In testimony whereof, we have hereunto set our hands.

JOHN W. LAKE.
